UNITED STATES PATENT OFFICE.

JOHN B. DAVIS, OF WHEELING, WEST VIRGINIA.

SAFETY-SWITCH CONSTRUCTION FOR RAILWAYS.

Application filed January 21, 1925. Serial No. 3,860.

The object of my invention is the provision of a simple, easily adjusted and strong safety switch construction, calculated to prevent derailment when a train is passing 5 the switch.

The invention will be fully understood from the following description and claim when the same is read in connection with the drawings, accompanying and forming 10 part of this specification, in which:—

Figure 1 is a plan view of a switch embodying the preferred form of my invention.

Figure 2 is an enlarged plan showing my 15 novel safety construction set for a clear main track.

Figure 3 is a cross section on line 3—3 of Figure 2.

Figure 4 is an enlarged diametrical section through the signal lamp stand.

Similar numerals of reference designate corresponding parts in all of the views of the drawings.

I show in Figure 1 main line track rails 25 1 and 2, switch rails 3 and 4 leading into a turnout 5, a transverse connection 6 between the switch rails 3 and 4 and a rotary member 7, and an appropriate handle 8 on said rotary member for turning the same 30 about its axis and thereby adjusting the switch rails. I also show a lamp stand 8 in which is journaled an upright rock shaft 9, equipped with a signal lamp 10 and also 35 equipped with a rotary disk 11, connected through a rod 12 with the said rotary member 7. Manifestly, when the member 7 is turned about its axis to adjust the switch rails 3 and 4, the signal lamp will be turned 40 to indicate the state of the switch and the disk 11 will also be turned, the latter for the movement of the pivoted frog point 12, comprised in my novel safety construction, the said point 12 being pivoted at 13, and being connected by a rod 14 with the said 45 disk 11.

The point 12 is shown in cross section in Figure 3, and by reference to said figure it will be understood that the point 12 is provided with a wide base 15 having rounded 50 edges; also, that the rod 14 is connected to the point 12 through the medium of a screw 16, threaded into the base 15 and pivotally connected at 17 to the rod 14.

In addition to the point 12 characterized 55 as described, my novel safety construction includes a base plate 18, spiked at 19 to

cross ties 20 and a V-shaped frog 21 riveted or otherwise connected at 22 in a fixed manner to and on the plate 18. The arms of the frog 21 adjacent to the heels of the 60 rails 3 and 4 have their opposed sides recessed as designated by 23 and best shown in Figure 3, each recess including a lower undercut portion 24 adapted to receive one side of the frog point base 15 with a view 65 to preventing casual upward movement of said point 12 when the same is positioned against either of the said arms. Manifestly, when the point 12 is arranged as shown in Figure 2, a continuous main truck rail 70 will be afforded which by cooperation with the flanges of the wheels of a passing train will preclude derailment of the train at the frog. Again, when the point 12 is moved to the position opposite to that shown in 75 Figure 2, a continuous rail and a continuous engagement for the flanges of the wheels of a train will be afforded between the switch rail 3 and the portion of the frog 21 at the right of Figure 2. Notwithstanding the 80 practical advantages of my novel construction, it will be apparent that the construction is simple and inexpensive; also, that when the point 12 is positioned against either of the recessed frog arms, the point 85 12 will not only be held against upward movement by the frog arm, but will be braced and reinforced against lateral movement by said frog arms.

In the preferred embodiment of my invention best shown in Figure 2, the recesses 23 are formed by offsetting the frog arms. This manifestly contributes to the strength and durability of the frog and assures 90 strong bracing of the point 12 in both positions of the same.

I have specifically described the preferred embodiment of my invention in order to impart an exact understanding of said embodiment. I do not desire, however, to 100 confine myself to the specific description herein, my novel invention being defined by my appended claim within the scope of which changes may be made without departing from my invention.

Having described my invention, what I 105 claim and desire to secure by Letters-Patent, is:—

In a railway construction, the combination with main track rails, turnout rails and 110 movable switch rails, of a plate fixed under the continuous portions of the main track,

turnout and switch rails, a frog fixed with respect to said plate and having divergent arms alined with the heel portions of the switch rails and also having recesses in the opposed sides of said arms and undercut chambers in communication with said recesses, and a frog point pivoted to said frog and movable in the space between the re-

cessed arms thereof and having a comparatively wide base the edge portions of which are adapted to enter the undercut chambers in communication with the recesses of the arms, for the purpose set forth. 10

In testimony whereof I affix my signature.

JOHN B. DAVIS.
